UNITED STATES PATENT OFFICE

ROSE B. QUINE, OF NEWTON, MASSACHUSETTS

APPAREL GARMENT

Application filed July 12, 1932. Serial No. 622,133.

This invention relates to a garment of the corset type and including a body-embracing band composed of sections connected at the front of the garment by positive or non-adjustable fasteners, and adjustably connected at the back by means including eyelets and a lacing.

The invention relates particularly to a garment thus characterized which includes means caused by the contraction of the band to exert supporting pressure on the sacro-iliac region of the wearer's body, different horizontal zones of the band being separately contractible to exert suitable pressure on other portions of the body.

The objects of the invention are to provide improved means for contracting the band as required to render the garment variously adjustable.

20 Of the accompanying drawings forming a part of this specification,—

Figure 1 is a front view, and Figure 2 a rear view showing a garment embodying the invention adjusted on the wearer's body.

25 Figure 3 is a view showing the outer side of the opened garment.

Figures 4 and 5 show diagrammatically the two confiners hereinafter described.

Figure 6 is a view showing the inner side 30 of the opened garment.

Figure 7 is a section on line 7—7 of Figure 1.

Figure 8 is a partial section on line 8—8 of Figure 1.

35 Figure 9 is a side view of the preferred buckle constituting an element of each confiner.

Figure 10 is a view similar to Figure 9 showing portions of the confiner straps connected by the buckle.

Figure 11 is a section on line 11—11 of Figure 10.

The same reference characters indicate the 45 same parts in all of the figures.

In the drawings 12 and 13 designate the two sections of the garment, said sections having substantially vertical rear edges provided with eyelets 14 and substantially vertical front edges provided with fasteners

such as hooks 15 and eyes 16, whereby they may be positively connected.

In the embodiment here shown the sections include body portions constituting the back and sides of the band and extensions 17 and 18 constituting the ends of a horizontal upper zone of the band, the rear vertical edges of the sections being longer than the front vertical edges which are formed on said extensions. The eyelets 14 in said rear edges constitute continuous rows coextensive with said edges.

The lower ends of the body portions of the sections project below the lower ends of the extensions 17 and 18.

19 designates tabs which may be of any suitable flexible, and preferably elastic fabric, and have attached end portions secured to the band sections, as by stitches 20, adjacent the vertical rear edges of the sections, and free end portions extending toward said rear edges and provided with eyelets 21.

Said tabs are within the band sections and are spaced from the upper and lower ends thereof. The tabs are formed and arranged to bear on the sacro-iliac region of the body when the garment is in use.

The preferred embodiment of the garment includes upper and lower adjusters of novel construction adapted to contract the band after the front edges thereof have been connected by the fasteners 15, 16, the lower adjuster being adapted also to tension the tabs 19, and cause pressure thereof on the sacro-iliac region.

The upper adjuster includes a pair of anchored outer straps 22, having outer ends 23 located within the band sections, and fixed thereto as by stitches 24, and free ends extending through slits 25 in the band sections, and upon the outer surfaces of said sections toward the rear edges thereof. Said adjuster includes also a pair of free inner straps 26 having buckles 27, preferably of the well known type shown by Figures 9, 10 and 11 fixed to the inner straps 26 and adapted to engage the anchored straps 22, and a plurality of looped flexible tapes each composed of end portions 28 fixed to the inner straps and neck portions 29 connecting the end por-

tions and extending through the upper eyelets 14 in the band sections as shown by Figures 6 and 7.

The arrangement is such that when strain is exerted on the anchored straps 22 the upper eyeleted ends of the band sections are drawn toward each other and confined at any desired distance apart by the buckles 27.

The lower adjuster includes duplicates of the above described elements of the upper adjuster, the two adjusters being practically identical with each other, and differing only in that the neck portions 30 of the tapes of the lower adjuster are engaged with the eyelets 21 of the tabs 19, as shown by Figures 6 and 8, the arrangement being such that when strain is exerted on the anchored straps 22 of the lower adjuster, the tabs are tensioned and caused to exert supporting pressure on the sacro-iliac region, the lower adjuster at the same time exerting contracting pressure on the band sections through said tabs.

The arrangement is such that an upper zone of the band is contractible by the upper adjuster and a middle zone by the lower adjuster. The contraction of the upper zone causes pressure on the diaphragm, and the contraction of the middle zone causes pressure on the abdomen.

The lower portions of the band sections project below the middle zone and constitute a lower zone adapted to be contracted by an independent lacing 32 engaged with eyelets in the lower portions of the rear edges of the sections.

I attach importance to the fact that the attached outer ends of the anchored straps 22 are located within the band sections, and emerge therefrom through slits 25 in said sections. This arrangement reduces to a minimum the strap material bearing on the external surfaces of the band sections, and contributes to the external smoothness of the adjusted garment. A smooth external surface is a desideratum in a garment of this character.

I claim:

1. An apparel garment comprising a sectional back-laced body-embracing band, flexible tabs having end portions attached to the band sections adjacent the rear edges thereof, and free ends extending toward said rear edges and provided with eyelets, said tabs being within the band on a middle zone thereof, and formed and arranged to bear on the sacro-iliac region, a lower adjuster adapted to tension said tabs and cause pressure thereof on said region, and to contract the middle zone of the band, said adjuster including a pair of anchored outer straps having outer ends located within, and fixed to, the band sections at the middle zone of the band, and free ends extending through slits in said middle zone, and along the outer

surface of the band toward the rear edges thereof, a pair of free inner straps having buckles engaging the anchored straps to maintain a tensioned condition of said adjuster, and a plurality of looped flexible tapes composed of end portions fixed to the inner straps, and neck portions connecting the end portions and extending through the tab eyelets, and through eyelets in the rear edges of the body sections, the arrangement being such that when tensioning strain is exerted on the outer straps the tabs are tensioned and caused to exert pressure on the sacro-iliac region, and contract the middle zone of the band, and an upper adjuster whose elements are duplicates of those of the lower adjuster, the anchored outer straps of the upper adjuster having outer ends located within, and fixed to, the band sections at the upper zone of the band, and extending through slits in said upper zone, the neck portions of the tapes of the upper adjuster extending through eyelets in the band sections, so that the upper adjuster is adapted to contract the upper zone of the band, the location of the fixed ends of the anchored straps of the two adjusters within the band sections, and the slits in said sections through which said straps extend, contributing to the external smoothness of the adjusted garment.

2. An apparel garment as specified by claim 1, the said band including a lower zone on which portions of the rear edges of the band sections are formed, and an independent lacing connecting said rear edge portions.

In testimony whereof I have affixed my signature.

ROSE B. QUINE.
